UNITED STATES PATENT OFFICE.

SAMUEL CRAWFORD IRVINE, OF BELFAST, IRELAND.

FLAX AND LIKE PULLING OR HARVESTING MACHINE.

Application filed January 5, 1923. Serial No. 610,864.

To whom it may concern:

Be it known that I, SAMUEL CRAWFORD IRVINE, of 67 Cliftonpark Avenue, Belfast, Ireland, a subject of the King of Great Britain and Ireland, have invented certain new and useful Improvements Relating to Flax and like Pulling or Harvesting Machines, of which the following is a specification.

This invention relates to flax, and like pulling or harvesting machines, having means whereby the flax, or the like is gripped between a number of fixed and movable pins or fingers to pull the same out of the ground, and to release it at a suitable point, said pins or fingers being carried on a frame rotated by gearing from the road wheels.

Under this invention I provide means adapted to engage the pulled flax at a point where it is released from the gripping pins, or fingers, and to deliver it to the rear of the machine, consisting of a device comprising a number of pins, in the form of a comb carried on a spindle, one end of the latter being connected to a member carried by an endless chain, whilst on the other end thereof is secured another member connected to an endless chain, and a double arm lever having rollers which engage a cam supported by the framework of the machine.

The invention further consists in the provision of means for lifting fallen flax or the like, so that it can be gripped by the gripping pins, said means consisting of a rod, or bar, or equivalent one end of which is slidably carried in a slotted bar connected with the framework of the machine, whilst the other end of the bar or rod extends towards the front of the machine, and is pivotally connected with a member carried by an endless chain, that is rotated through gearing from the road wheels, so that the rod, or bar, will be given a backward and downward and then forward and upward movement to lift the fallen flax so as to be gripped by the gripping pins or fingers.

The invention will now be described with reference to the accompanying drawings whereon:

Fig. 1 is a plan view of a machine constructed in accordance with the invention.

Fig. 2 is an end elevation (looking in the direction of the arrow *y*) of the machine.

Fig. 3 is a sectional end elevation taken on the line *x-x* Fig. 1.

55 Referring to the drawings:

1 is the rotating frame, 2 the fixed pins or fingers, 3 the movable pins or fingers, 4 the cam controlling the slideable bars carrying the fingers 3, 5 the axle carrying the rotating frame and 6 the machine framework.

Supported on spindles 7^a and 8^a mounted in bearings carried by the framework 6, are two rollers 7 and 8, which support the pulled flax as it is carried back by the comb hereinafter described.

The roller 7 is driven from the axle 5 by a chain and sprocket drive 9, whilst the roller 8 is driven from the spindle 7^a of the roller 7 by a chain and sprocket drive 10. These rollers assist the backward movement of the pulled flax.

A member 11 connected to the chain of the chain and sprocket drive 10 is mounted on one end of a spindle 12, on the other end of which is secured a member 13 connected to the chain of the chain and sprocket drive 7^a on the spindles 7^a and 8^a of the rollers 7 and 8.

The inner end of the spindle 12 is connected to a double arm member 15, having rollers 16 and 17, adapted to engage a cam 18 supported by brackets 18^a and 18^b from the machine framework 6.

The cam 18 is made with a cam race or groove 18^c extending around same, this cam race controlling the movement of the roller 17 on the member 15. A groove 18^d extending round a portion of the cam 18, and on the outside of the groove 18^c controls the movement of the roller 16.

Secured on the spindle 12 is a bar 20 having secured thereto a plurality of pins 21 forming a comb. The movement of the rollers 16 and 17 in the cam 18 imparts the necessary movement to the comb, required, to bring the same into engagement with the flax as it is being released by the gripping pins 2 and 3, and to carry the flax over to the rear of the machine.

The arrangement is such that when the flax is being pulled by the turning of the frame 1 and gripped between the gripping pins or fingers 2 and 3, the rollers 16 and 17 on the double arm member 15 will be moved round the cam in the direction of the arrow *Z*, and on the roller 16 entering the groove 18^d, the comb will be brought into a horizontal position underneath the rollers 7 and 8, and as

the said cam roller 16 reaches the point 18^e of the cam it will be released from operative connection with the same by the groove 18^d, and the comb will decline towards the ground.

When the roller 17 reaches the ground, the roller 16 will be moved round the cam in the direction of the arrow *Z*, and on the roller 16 entering the groove 18^d, the comb will be brought into a horizontal position underneath the rollers 7 and 8, and as

the said cam roller 16 reaches the point 18^e of the cam it will be released from operative connection with the same by the groove 18^d, and the comb will decline towards the ground.

When the roller 17 reaches the ground, the roller 16 will be moved round the cam in the direction of the arrow *Z*, and on the roller 16 entering the groove 18^d, the comb will be brought into a horizontal position underneath the rollers 7 and 8, and as

the said cam roller 16 reaches the point 18^e of the cam it will be released from operative connection with the same by the groove 18^d, and the comb will decline towards the ground.

When the roller 17 reaches the ground, the roller 16 will be moved round the cam in the direction of the arrow *Z*, and on the roller 16 entering the groove 18^d, the comb will be brought into a horizontal position underneath the rollers 7 and 8, and as

the said cam roller 16 reaches the point 18^e of the cam it will be released from operative connection with the same by the groove 18^d, and the comb will decline towards the ground.

point 18^c of the groove 18^c, the comb will be turned upwards towards the flax and into engagement therewith, and on the roller 17 reaching the top portion of the cam race 5 of the cam, the comb is caused to incline towards the back of the machine and the disengaged ends of the flax will rest on and be assisted backwards by the rollers 7 and 8 as it is being carried over by the comb to 10 the rear of the machine.

One end 22^a of a bar 22 is movably supported in a slotted bar 23 supported by the frame work 6 of the machine. The bar is connected near the centre thereof to a member 15 24 connected to the chain of the chain and sprocket drive 25, mounted on the spindles 7^a and 8^a of the rollers 7 and 8, the arrangement being such that when the flax is being pulled by the gripping pins or fingers 20 2^a and 3 the rotation of the chain and sprocket drive 25 will cause the bar 22 to be given a backward and downward and then forward and upward movement, so that any fallen flax will be lifted towards and carried 25 into engagement with the gripping pins or fingers. A similar arrangement may, if desired, be provided at the other side of the machine to lift the fallen flax towards the gripping fingers.

30 Having now fully described my invention, what I claim and desire to secure by Letters Patent is:—

1. In a flax or like pulling and harvesting machine, the combination with means 35 for pulling the material out of the ground and releasing it at a suitable point, of a comb for engaging the pulled material and means for moving said comb to deposit said material away from said pulling means.

40 2. In a flax or like pulling and harvesting machine, the combination with means for pulling the material out of the ground and releasing it at a suitable point, of a comb for engaging the pulled material and 45 means for imparting a combined angular and translatory movement to said comb in order to deposit said material away from said pulling means.

50 3. In a flax or like pulling and harvesting machine, the combination with means for pulling the material out of the ground and releasing it at a suitable point, of a comb for engaging the pulled material, a spindle supporting said comb, means for 55 positively rotating said spindle, members mounted on said spindle and carried by said positively rotating means, and means for positively rotating said rollers from the road wheels of the machine for imparting a 60 combined angular and translatory movement to the comb in order to engage the pulled material.

65 4. In a flax or like pulling and harvesting machine, the combination with means for pulling the material out of the ground and

releasing it at a suitable point of a comb for engaging the pulled material, a spindle supporting said comb, members supported by said spindle and carried by endless chains, supporting rollers for the pulled material, gear wheels on the supporting rollers for rotating said chains, a double arm lever mounted on said spindle, guide rollers on said lever, and means engaging said guide rollers for imparting a combined angular 70 and translatory movement to the comb in order to engage and deposit the pulled material away from said pulling means. 75

5. In a flax or like pulling and harvesting machine, the combination with means for pulling the material out of the ground and releasing it at a suitable point, of a comb for engaging the pulled material, a spindle supporting said comb, endless chains rotating said spindle, members supported on said chains, supporting rollers for the pulled material, gear wheels for rotating said chains mounted on the axles of the supporting rollers, a double arm lever on said spindle, guide rollers on said lever, and a cam engaging the said rollers for imparting angular and translatory movement to the comb in order to engage and deposit the pulled material away from the said pulling means. 90

6. In a flax or like pulling and harvesting machine, the combination with means for pulling the material out of the ground and releasing it at a suitable point, of a comb for engaging the pulled material, a spindle supporting said comb, endless chains rotating said spindle, members supported on said chains, supporting rollers for the pulled material, gear wheels for rotating said chains mounted on the axles of the supporting rollers, a double arm lever on said spindle, guide rollers on said lever, a cam engaging said guide rollers, a cam race on said cam for controlling the movement of one guide roller and a cam race extending partially round said cam for controlling the movement of the other guide roller, so as to impart a combined angular and translatory movement to the comb in order to engage and deposit the pulled material away from the said pulling means. 100 105 110

7. In a flax or like pulling and harvesting machine, the combination with means for pulling the material out of the ground and releasing it at a suitable point, a side bar for engaging fallen material at the side of the machine for lifting same into engagement with the means for pulling the material out of the ground, and a comb for engaging the pulled material, and means for moving said comb to deposit said material away from said pulling means. 115 120 125

8. In a flax or like pulling and harvesting machine, the combination with means for pulling the material out of the ground and releasing it at a suitable point, of a side 130

bar for engaging fallen material at the side of the machine and fitting same into engagement with the means for pulling the material out of the ground, a comb for engaging the pulled material and means for imparting a combined angular and translatory movement to said comb in order to deposit said material away from said pulling means.

10 9. In a flax or like pulling and harvesting machine the combination with means for pulling the material out of the ground and releasing it at a suitable point, of a side bar, means for positively reciprocating said bar and means for guiding said bar in order to impart a backward and forward movement and then upward and forward movement to the bar for lifting the fallen material into engagement with the means for pulling the material out of the ground, a comb for engaging the pulled material, and means for imparting a combined angular and translatory movement to the comb in order to deposit said material away from the said pulling means.

10 10. In a flax or like pulling and harvesting machine, the combination with means for pulling the material out of the ground and releasing it at a suitable point, of a side bar, a member mounted on said bar and carried by positively reciprocating means, rollers for supporting the pulled material engaging said means, means for positively rotating said rollers from the road wheels of the machine, means for guiding said bar in order to impart a backward and forward movement, and then upward and forward movement to the bar for lifting fallen material into engagement with the means for pulling the material out of the ground, a comb for engaging the pulled material, and means for imparting a combined angular and translatory movement to the comb in order to deposit said material away from the said pulling means.

11 11. In a flax or like pulling or harvesting machine, the combination with means for pulling the material out of the ground and releasing it at a suitable point, of a side bar, a member mounted on said bar and carried by an endless chain, supporting rollers for the pulled material, gear wheels on the sup-

porting rollers engaging said endless chain, means for positively rotating said rollers from the road wheels of the machine, means 55 for guiding the bar in order to impart a backward and forward movement, and then upward and forward movement to the bar for lifting fallen material into engagement with means for pulling the material out of 60 the ground, a comb for engaging the pulled material, a spindle supporting said comb, means for positively rotating said spindle, members mounted on said spindle and carried by said positively rotating means, rollers 65 for supporting the pulled material engaging said means, and means for positively rotating said rollers from the road wheels of the machine.

12. In a flax or like pulling and harvesting machine, the combination with means for pulling the material out of the ground and releasing it at a suitable point, of a side bar, a member mounted on said bar and carried by an endless chain, supporting rollers 70 for the pulled material, gear wheels on said supporting rollers engaging said endless chain, a bracket supported on the frame of the machine, a guideway in said bracket and means for slidably reciprocating said 75 bar in said bracket in order to impart a backward and forward movement, and then upward and forward movement to the bar for lifting fallen flax into engagement with means for pulling the material out of the 80 ground, a comb for engaging the pulled material, a spindle supporting said comb, endless chains rotating said spindle, members supported on said chains, supporting 85 rollers for the pulled material, gear wheels 90 for rotating said chains mounted on the axles of the supporting rollers, a double arm lever on said spindle, guide rollers on said lever, and a cam engaging said guide 95 rollers for imparting an angular and translatory movement to the comb in order to engage and deposit the pulled material away from the said pulling means.

In testimony whereof I affix my signature in presence of two witnesses.

SAMUEL CRAWFORD IRVINE.
